UNITED STATES PATENT OFFICE.

PHILIP LIBONATI, OF NEW YORK, N. Y.

BOX-OPENER.

1,135,593.

Specification of Letters Patent. Patented Apr. 13, 1915.

Application filed November 10, 1913. Serial No. 800,102.

To all whom it may concern:

Be it known that I, PHILIP LIBONATI, a citizen of the United States of America, residing at New York city, in the county of 5 New York and State of New York, have invented certain new and useful Improvements in Box-Openers, of which the following is a specification.

This invention relates to box openers, and 10 is designed more particularly for the purpose of starting or lifting the lid of a box of shoe polish or other material contained in a tin box so that the lid may be readily removed by hand.

15 The tin boxes for containing shoe polish or other materials are generally fitted with a practically air tight cover, the purpose being to prevent evaporation or deterioration of the contents of the box. These lids 20 are tightly fitted to the boxes and cannot be readily removed by hand, without first being loosened or lifted.

One of the principal objects of my invention is to provide reliable and efficient means 25 for lifting or starting the cover from the box so that it can be readily removed by hand.

Another object of the invention is to provide simple and inexpensive means to be 30 pivotally connected to the box for loosening the cover, said means adapted to lie close to the box and to conform to the curvature thereof, entirely out of the way, when not required for use, and which can be quickly 35 operated for loosening the cover.

Still another object of the invention is to provide a box opener made from a single piece of spring material which will normally conform to the curvature of the box, which 40 will be pivoted to the body of the box to be turned in a position readily to loosen the cover, thus providing a box opener of simple construction which can be quickly connected to the box and readily operated for the purpose referred to.

45 These and other objects may be attained by means of the construction illustrated in the accompanying drawings, in which,—

Figure 1 is a perspective view of a box of 50 the usual construction designed for containing shoe polish, said box having pivotally connected thereto an opener made in accordance with this invention. Fig. 2 is a

side elevation of the same showing the 55 opener in full lines in position for packing and shipping, and when not required for use, and in dotted lines showing the lid slightly lifted from the box by the opener. Fig. 3 is a plan view of a portion of the box and the opener connected thereto. Fig. 4 60 is a detailed perspective view of the opener member removed from the box. Fig. 5 is a vertical sectional view.

Referring to the drawing the numeral 1 designates the body of a box, such as is generally used for containing shoe polish, and 2 65 is the cover of the same and usually provided with an outwardly turned terminal flange 3.

The opener comprises a flat piece of resilient metal provided with an angular lip 4 at 70 one end, and at the other end with an outwardly turned finger-hold 5. The spring member is curved to conform to the contour of the box and the lip 4 is curved to bear against the side of the box as shown. The 75 opener is connected to the box by a pin 6 which permits the opener to have a pivotal movement thereon.

As a modification of the construction thus far described, a slot 7 may be formed in the 80 opener and when the member is thrown into a vertical position upon the pin 6 it may be moved upward to release the cover 2. It will be understood that should the construction with the slot 7 be utilized, the pivotal point 85 should be closer to the curved end 4 of the opener, in order that the opener may be swung into a position at right angles to the box and pushed upward to release the cover.

From the foregoing it will be obvious that 90 the opener is simple in construction, can readily be stamped up from a single piece of resilient metal or material, and can be quickly connected to the box by a pivotal pin 6. When the opener is swung in alignment with the lower edge of the cover 2, it 95 is entirely out of the way and occupies but little space.

What is claimed is:

In combination with a round box and its 100 cover, a spring lever connected underneath the cover to the side of the box, by a pivot pin, said lever being curved to conform to the contour of the side of the box, said lever having an angular lip at one end to engage 105 the box cover when the lever is operated, and

a finger-hold at the opposite end of the lever, said lever being provided with a longitudinal slot through which the pivot pin passes to permit the lever to move lengthwise to engage the cover and loosen the same from the box when turned in operable position.

In testimony whereof I affix my signature in presence of two witnesses.

PHILIP LIBONATI.
